UNITED STATES PATENT OFFICE.

JOHN O. JOHNSON, OTTO H. JOHNSON, AND CHARLES W. JOHNSON, OF NEW HAMPTON,
IOWA.

TAMPING-MACHINE FOR CONCRETE BLOCKS.

1,277,081.

Specification of Letters Patent. Patented Aug. 27, 1918.

Application filed June 28, 1917. Serial No. 177,509.

To all whom it may concern:

Be it known that we, JOHN O. JOHNSON, OTTO H. JOHNSON, and CHARLES W. JOHNSON, citizens of the United States, residing 5 at New Hampton, in the county of Chickasaw and State of Iowa, have invented certain new and useful Improvements in Tamping-Machines for Concrete Blocks, of which the following is a specification.

10 This invention relates to new and useful improvements in tamping machine for concrete blocks.

The primary object of the invention is the provision of a tamping machine that may 15 be readily moved about as desired and advantageously in tamping concrete within the molds during the manufacture of building blocks or similar articles.

A further object of the device is to provide 20 a tamping machine capable of rapid operation in tamping plastic compositions into desirable molds, the device possessing great strength and being adjustable whereby the surface being tamped or acted upon by 25 the device, may be changed at the will of the operator.

With these general objects in view and others that will appear as the nature of the invention is better understood, the same consists 30 in the novel combination and arrangement of parts hereinafter fully described, illustrated in the accompanying drawings and pointed out in the appended claims.

In the drawing forming a part of this 35 application and in which like reference characters designate corresponding parts throughout the several views,

Figure 1 is a front elevation of the device partially broken away.

40 Fig. 2 is a central, vertical, sectional view thereof, portions being shown by dotted lines in their adjusted positions.

Fig. 3 is a transverse sectional view enlarged taken upon line III—III of Fig. 4, 45 and

Fig. 4 is a sectional view taken upon line IV—IV of Fig. 3.

Referring more in detail to the drawing 50 a rectangular frame 10, is provided having similar opposite top and bottom ends 11, and 12 respectively, each of said ends being preferably formed of a pair of angle irons 13, spaced apart and connected to the opposite longitudinal upright sides 14, of the 55 frame by corner brackets 15.

A plurality of tamping bars 16 arranged in parallelism slidably positioned upright within the spaces 17, between the angle irons 13, of each of the frame ends, channeled positioning blocks 18, being arranged 60 upon each of the angle irons 13 serving as guides for the tamping bars. Two spaced bolts 19 are provided for each pair of blocks 18 fitting within side grooves 20 of the said blocks, the said bolts 19 being laterally slid- 65 able within longitudinal slots 21 arranged through the angle irons 13.

By this arrangement it will be evident that the tamping bars 16 may be shifted transversely of the frame 10 and positioned 70 closer together or farther apart as may be found desirable, the shifting operation being readily accomplished by adjusting the lock nuts 22 upon the bolts 19. Tamping feet or pounders 23, are provided upon the 75 lower ends of the bars 16 for engaging the plastic material being operated upon during the lowering of the bars 16, during the longitudinal movement thereof.

A power shaft 24 is journaled transversely 80 of the frame 10, provided with an operating pulley 25, upon one end thereof, while a separate sprocket wheel 26 is adjustably mounted upon the shaft 24, for each of the bars 16, by means of hubs 27, having suitable 85 adjustment retaining means such as the screws 28. A driven shaft 29 is journaled upon the frame 10, beneath the shaft 24, which is also provided with a sprocket wheel 26' for each of the tamping bars 16, the said 90 wheels 26' being retained in adjusted positions upon the shaft 29 by any suitable means such as the screws 28'.

Sprocket chains 30 are arranged over the sprocket wheels 26 and 26' directly in the 95 rear of each of the bars 16, certain of the links of each chain 30 being provided with a fork 31, adapted for moving upwardly beneath and engaging a lift collar 32, with which each of the tamping bars 16 is provided. It will be obvious that upon turning the shaft 24, for moving the chains 15, so that the forks 31 will move upwardly in standing relation with the bars 16, the said forks will engage beneath the lift collar 32, 100 thereby elevating the bars 16, until the forks permit the collars to pass thereover in a tripping movement as the links of the chain 30 which carry the forks 31 pass rearwardly 105 over the upper sprocket wheel 26. It will be 110

obvious that the forks 31 may be positioned at different points upon the several chains 30 and that the collar 32 will thereby be engaged by the forks at different times, 5 while such arrangement may be made as desirable for operating all of the bars 16, simultaneously, each one separately or in any desired order or combination.

A suitable guard 33 is preferably arranged 10 rearwardly of the chains 30, for protecting the same while a similar guard 34 may be positioned between the chain sides as illustrated in section in Fig. 2 of the drawing.

A ready means is provided for maintaining either one or all of the bars 16 inoperative, when desired, the same consisting of leaf springs 35, adjustably secured upon a transverse bar 36, at the forward side of the frame 10, the said springs being of sufficient length to engage beneath the forwardly projecting heel 37, of each adjacently positioned lift collar 32 when the bars 16 carrying such collar are substantially at the limit of their upward travel. The springs 35 being adjustable longitudinally of the bar 36, are maintained in position by screws 38. A releasing means for the springs 35 consists of a plurality of cams 39, carried by a rod 40 transversely journaled through the frame 10 and having a suitable turning means such as the lever 41.

When the lever 41 is moved to its horizontal position, the cams 39 engage the springs 35 retaining the same forwardly of the paths of movement of the collars 32 as illustrated in Fig. 2 of the drawing. When the lever 41 is elevated, the cams 39 are released from the springs 35 permitting the latter to move rearwardly in substantial contact with the bars 16 and engaging beneath the collar 32 upon the upward movement of the bars, thereby retaining the latter inoperatively elevated, as shown by dotted lines in Fig. 2. It will be understood that 45 different sets of cams 39 may be so arranged upon the rod 40, as to render it possible to maintain only a part of the rods 16 elevated while the remaining rods are permitted to operate, this being readily accomplished by 50 having four cams 39 arranged in alignment upon the rod 40 for simultaneously releasing all of the springs 35, while other cams, such as two in number, may be positioned upon the rod 40 extending at a different angle for engaging only two of the springs 35, for instance the outer two springs and whereby the outer two bars 16 may be permitted to operate while the inner two bars will be inoperatively arranged by means of 55 their respective springs 35, being in engagement with the lift collars 32 thereof.

The complete operation of the device will be apparent from this detailed description thereof, it being seen that the tamping feet 23, may be shifted relatively of each other

for tamping the desired area while the bars 16 may be simultaneously or separately elevated and permitted to freely descend and at which times the weight of the bars 16 and the feet 23 are relied upon for imparting 70 the necessary force to the operating strokes of the tampers.

A serviceable device is arranged possessing great strength and which may be operated either by hand or by power for rapidly 75 tamping plastic materials within suitable molds and while the form of the invention herein set forth is believed to be preferable, it is understood that minor changes may be made therein without departing from the 80 spirit and scope of the invention as claimed.

What we claim as new is:

1. A tamping machine comprising a frame, having upper and lower ends formed of spaced bars arranged with longitudinal 85 slots, pairs of spaced bolts arranged within said slots shiftable transversely of the frame, pairs of guide blocks arranged between each pair of said bolts, tamping bars longitudinally slidably arranged vertically through the said pairs of blocks at the top and bottom of the frame, tamping feet upon the lower ends of said bars, a power and a driven shaft transversely journaled upon said frame, sprocket wheels upon said 90 shafts, sprocket chains upon said wheels arranged directly rearwardly of the said bars, lift collars upon said bars, elevating forks carried by said chains adapted for upward movement beneath the said collars whereby 100 the tamping bars are elevated and released during the turning of the said shafts when the device is in operation, retaining springs for the said bars adapted for engagement beneath the said collars and cam releasing 105 means for the said springs.

2. A tamping machine comprising a rectangular frame including spaced slides, top and bottom members secured to the upper and lower ends of the sides and formed of spaced angle irons, pairs of spaced guide-blocks slidably mounted between said irons, means for adjustably securing said blocks to said irons, a plurality of tamping bars slidably and adjustably mounted in said frames and each bar extending through a pair of guide-blocks in the top and bottom irons, means for raising said tamping bars, a shaft mounted on the sides forwardly of said tamping bars, cams adjustably mounted on said shaft, means supported by said sides beneath said cam-shaft for engagement with said cams, and means for actuating said cam-shaft for engagement with said cams, and cams whereby the first-named means may be moved into tamping-bar engaging position to hold the latter against operation.

3. A tamping machine comprising a rectangular frame including spaced sides, top and bottom members secured to the upper 130

and lower ends of the sides and formed of spaced angle irons, pairs of spaced guide-blocks slidably mounted between said irons, means for adjustably securing said blocks to said irons, a plurality of tamping bars slidably and adjustably mounted in said frames and each bar extending through a pair of guide-blocks in the top and bottom irons, means for raising said tamping bars, 5 a shaft journaled to the forward sides of said sides of the frame, spaced cams adjustably secured to said shaft, a second shaft journaled to the outer surfaces of said sides 10

beneath said first-named shaft, spaced vertically-extending springs adjustably secured 15 to said second shaft and normally engaging said cams, and means for actuating said first shaft and cams for moving said springs into tamping-bar position to hold the latter against movement. 20

In testimony whereof we affix our signatures.

JOHN O. JOHNSON.

OTTO H. JOHNSON.

CHARLES W. JOHNSON.
